CONCRETE CYLINDER FORM SLITTING MACHINE

Richard B. Fleming, Brooklyn, N. Y.

Application January 26, 1955, Serial No. 484,266

1 Claim. (Cl. 164—77)

This invention relates to improvements in devices for releasing moulded concrete cylinders and other shapes from confinement in cylindrical sheet forms and other similar molds.

An object of the invention is to provide a novel and improved device whereby a mold or form in which a concrete cylinder or other shape is cast or contained, may be stripped therefrom quickly and easily.

Another object of the invention is to provide a novel and improved concrete cylinder stripping machine in which there is a main frame including a support for the concrete object to be stripped, with cutting means for engaging the encasement of the concrete object and opening it out, and manual or machine operated traversing means for advancing the cutting means along the cutting path.

A further object of the invention is to provide a novel and improved concrete cylinder stripping machine in which the cutting means is so arranged as to exert only sufficient cutting effort to cut the encasement of the concrete cylinder, without scoring or otherwise damaging or injuring the cylinder itself.

Still another object of the invention is to provide a novel and improved concrete form stripping machine in which the form to be stripped is readily receivable in the main housing, for the stripping operation, and wherein, after the encasement is stripped from the form, or mold, the cylinder is readily moved out of the housing without the need for actual lifting of the concrete cylinder, and without damage thereto.

Still a further object of the invention is to provide a novel and improved concrete form stripping machine in which the entire construction is simple in design, includes a minimum of parts, and is highly effective in operation, permitting at low cost, the continuous successive stripping of a large number of concrete cylinders for test or other purposes, with the utmost in convenience to the operator of the machine.

These and other objects and advantages of the invention will become apparent from the following description of a preferred embodiment thereof, as illustrated in the accompanying drawings, forming a part hereof, and in which,

Figure 1 is a front elevational view of the machine, with a concrete cylinder disposed therein in partly cut disposition.

Figure 2 is a right end elevational view of the machine shown in Figure 1.

Figure 3 is a top plan view of the device shown in Figure 1.

Figure 4 is a longitudinal sectional elevational view taken substantially on plane 4—4 of Figure 3.

Figure 5 is a transverse sectional elevational detail view taken substantially on plane 5—5 of Figure 3, and showing only the parts at the planar viewing line.

In connection with molded or cast products, such as cement or concrete cylinders and other shapes, it is frequently necessary or important to remove or strip from the molded cylinder the encasement, which may be in

2

the form of a paperboard or cardboard hollow cylinder or the like, conforming to the curvature of the molded shape. Where such molded products are formed in large numbers, as for use as posts, supports, or the like, or as test samples for use in testing machines to determine the physical strength and deformation characteristics of the molded concrete, it is apparent that stripping each mold individually by hand is difficult and time consuming. The present device provides novel means for achieving the stripping of the confining encasement or mold form from the molded concrete cylinder or the like, with remarkable rapidity, and without damage to the concrete itself.

In order to understand clearly the nature of the invention, and the best means for carrying it out, reference may now be had to the drawings, in which like numerals denote similar parts throughout the several views.

As shown, there is a main base generally indicated at 10, and including a base floor 12, with upstanding first and second side flanges or walls 14 and 16, which may be integral with the base floor 12, as for example, in the shape of a channel structural member or the like. The device includes first and second side walls 18 and 20, the lower edges 22 of which are preferably seated upon the web 12 of the main base or channel 10, so that the lower portions of the front and rear edges 24 and 26 are seated firmly against the upstanding flanges 14 and 16 of the base channel 10, and preferably firmly secured or even welded thereto, so as to attain substantial rigidity and strength against deformation in use. As seen best in Figure 2, the upper portions of the end walls 18 and 20 may be upwardly divergent to attain the necessary width of the said walls at their upper portions, to accommodate the shafts shown, as at 30 and 32. It is thus seen from the views, that the shafts 30 and 32 have their outer ends extending in reduced form through the accommodating openings formed through the upper ends of the side walls 18 and 20, being secured to said walls by suitable fastening means, such as nuts 34 threaded onto the ends of the slide shafts 30 and 32.

A gear rack 40, having teeth 42 formed all along its lower surface, as seen best in Figures 1 and 4, is secured by screws or bolts 44 to the undersurfaces of supporting web walls 46, the webs 46 being in turn either welded or otherwise secured to or integrated with slide sleeves 48, which are of slightly greater inside diameter than the diameters of the slide shafts 30 and 32, and thus are able to slide freely along the slide shafts from left to right and vice versa, as seen in Figures 1, 4, and 3. Thus the rack 40, the web walls 46, and the slide sleeves 48 all are secured together in this manner as a unit, for movement together in a direction parallel to the axes of the shafts 30 and 32.

A pair of shaft supporting walls 50 and 52 are secured by screws or bolts 54 to the outer surfaces of the base channel flanges 14 and 16, and are preferably made of substantial thickness to avoid deformation or deflection under the stresses normally encountered thereby. The shaft supporting walls 50 and 52 are thus disposed preferably intermediate the end walls 18 and 20, and, as seen in Figure 3, are outwardly of the slide shafts 30 and 32, and thus out of the paths of movement of the slide sleeves or hollow hubs 48. Bearing bores 56 are formed through the bracket walls 50 and 52, to receive the turning shaft 58, and as shown, there is a gear or pinion 60 mounted on the shaft 58 for turning therewith, being secured by set screws 62 or the like threaded radially into the reduced gear sleeves 64 which are integral with the pinion 60, so as to turn with the shaft 58.

The teeth of the gear 60 being in mesh with the teeth on the rack 40, it is seen that turning the gear 60 results in longitudinal movement of the rack to the left

or right depending upon the direction of turning of the gear 60. A retaining sleeve 66 is secured on one end of the shaft 58 by means of a set screw or the like, and a handle receiving hub 68, having an extended hub sleeve 70 integral therewith, is mounted on the other end of the shaft 58, being secured thereto for turning with the shaft by means of a set screw 72. The handle receiving hub 68 has an opening 74 formed therethrough to receive the shank 76 of the handle 78, the position of the shank 76 being adjustable by loosening and tightening the set screw 79 as needed. A handle grip 80 is carried on the outer or distal end of the handle shank, being turnable on a handle grip pin 82 one end of which is threaded into or otherwise secured in an opening formed in the outer end of the handle shank 76.

It is thus apparent that turning the handle 78 in a clockwise direction as seen in Figures 1 and 4, turns the pinion 60, and hence moves the gear rack 40 to the right, while turning it in the counterclockwise direction retracts the gear rack to the left. An opening is formed at 88 in wall 18 to allow the left end of the rack 40 to extend freely therethrough when in extreme retracted position. A cutting or slitting wheel 90 having suitably sharpened cutting edge, is mounted on a small shaft or pin 92 extending across the opening in the space between the bifurcations 96 of the yoke 94, the yoke being secured to or carried by the yoke supporting shaft 98, which is preferably rectangular in cross section and extends through a correspondingly shaped opening 99 in the floor 101 of the housing 100. As seen best in Figure 5, the housing 100 is mounted on the right hand or forward end of the rack 40, by suitable means, such as the angle bracket 103, and may be formed in complementary housing halves 105 and 107 secured together by screws 128 or the like.

As seen in Figure 5, the rectangular post 98 may have a piston head 106 secured to its upper end, with a spring 110 disposed thereabove to exert downward cutting bias on the cutting or slitting wheel 90 under compression governed by the washer 130 carried by and movable with the lower end of the threaded compression adjusting screw 116. The screw 116 is threaded through an opening 122 in the top wall 112 of the housing 100, which is secured in any suitable manner to the housing, as by screws 114. A turning knob or handle 118 is mounted on the upper end of the adjustment screw 116 by means of a screw 120, to turn the screw 116.

The device shown is particularly useful in slitting the encasing cardboard or fibreboard covering 132 from a concrete or cement or other composition cylinder or other shape, such as shown at 134. The encased concrete cylinder 134 is placed in the machine, so as to rest upon the web or floor 12, with its right end against and in contact with the supporting stop member 140, as seen clearly in Figures 3 and 4. The flange 16 is partially cut away, as seen in Figure 4, to the right of location 142, and the cut extends almost to the end wall 20, thus allowing ready insertion of the cylinder to be stripped, and removal thereof when the slitting operation is completed, through this opening. A small rib stop member or inner positioning wall 138 is disposed as seen best in Figure 5, on the same side as the cut away opening in the flange 16, to furnish some support for the concrete cylinder while being stripped, but it is seen that it is simple to roll the stripped cylinder over this stop 138 when the slitting is finished, to the right as seen in Figure 5.

An opening 152 is formed in the right end wall 20, as seen best in Figures 2 and 4, to allow the right end of the rack 40 and the housing 100 to move therethrough without obstruction. By adjusting the handwheel 118, it is seen that the slitting or cutting pressure on the waxed cardboard cylinder 132 may be adjusted just to be enough to slit the same, avoiding damage to the concrete cylinder therebelow. If desired, a suitable stop

limit means may be provided to block movement of the cutting edge of wheel 90 below a predetermined level, depending upon the thickness of the casing 132.

It is thus seen that this is a very versatile instrument for its intended purpose. By mere manipulation of the cutting wheel handle 78 traverse of the cutting wheel is made quickly and easily, so that a large number of such cylinders may be stripped uniformly and within a short time. By adjustment of the dimensions, a variety of sizes of cylinders or other molds may be stripped.

Although I have described my invention in specific terms, it will be understood that various changes may be made in size, shape, materials and arrangement without departing from the spirit and scope of the invention as claimed.

I claim:

A device for stripping a form from a concrete-like form-encased mold, comprising a main base means in the form of a channel having edge flanges upturned 20 to define a trough for receiving said concrete-like form-encased mold, first and second end walls extending upwardly from said main base means in mutually spaced relationship to define said trough to receive said form-encased mold, inner positioning wall means carried by said 25 channel intermediate said edge flanges for precise positioning of said mold to bring its axis into stripping position, bracket wall means disposed intermediate said first and second end walls, pinion shaft means carried by said bracket wall means for rotation about the axis of said 30 pinion shaft means, a pinion gear carried by said pinion shaft means for turning therewith, overhead rail means formed of a pair of cylindrical shafts interconnecting said first and second end walls, first and second web means slidably engaging said pair of shafts in mutually 35 spaced relationship for slidable movement therealong, a rack secured to both said web means intermediate said pair of shafts for slidable movement therealong with said web means, said web means comprising hollow hub means for slidably receiving said shafts for said slidable engagement, said rack being in engagement with said pinion gear, so that said rack is longitudinally moved on turning of said pinion gear, crank means for turning said pinion shaft means, a cutting wheel head carried by said rack for movement therewith, and comprising 40 a cutting head housing defining a bore, a cutting wheel supporting shaft engaging said bore, yoke means on the lower portion of said shaft for carrying a form cutter wheel, for cutting said encasing form, resilient means acting between said cutting head housing and said cutting wheel supporting shaft for exerting cutting bias 45 on said shaft and said cutting wheel, and adjustment means including a threaded adjustment handwheel and shaft for regulating the degree of resilient bias, a cutting wheel means carried by said cutting wheel supporting shaft and oriented downwardly therefrom for slitting engagement with said form to be stripped from said mold, said first and second end walls having openings 50 formed therein through which said rack and cutting wheel is extensible, whereby full retraction and extension of said rack is possible, and so that on retraction of said rack, said mold is upwardly accessible.
